UNITED STATES PATENT OFFICE

WILLIAM JOSEPH LASCELLES, MAGNUS FRASER PETERSON, JOHN RUSSELL SCOTT, AND KENNETH McCLYMONT WILSON, OF MANCHESTER, ENGLAND, ASSIGNEES TO ADDRESSOGRAPH COMPANY, OF CLEVELAND, OHIO, A CORPORATION OF DELAWARE

PRINTING MACHINE

Application filed November 28, 1931, Serial No. 577,736, and in Great Britain September 2, 1930.

This invention relates to printing machines and more particularly to an auxiliary printing mechanism adapted for use with such machines.

One object of the invention is to provide a novel auxiliary printing mechanism embodying a portion operable from the printing member in a printing machine to operate a device associated with the printing mechanism.

Another object is to provide an auxiliary printing mechanism embodying a printing form including a part which moves into an inoperative position when the auxiliary printing mechanism is not arranged for proper operation.

A further object is to provide a counting device in association with an auxiliary printing mechanism so as to be operable thereby and to so arrange the counting device that unauthorized access thereto may be prevented.

A still further object is to provide an auxiliary printing mechanism of simple and economical construction and positive and efficient operation.

In the accompanying drawings wherein a selected embodiment of the invention is illustrated

Fig. 1 is a partial sectional view of the mechanism associated with an addressing machine;

Fig. 2 is a side view of the mechanism shown in Fig. 1 with the cover plates removed;

Fig. 3 is a plan view in which a portion of the housing is broken away; and

Fig. 4 is a detail sectional view taken substantially on the line 4—4 on Fig. 3.

The auxiliary printing mechanism shown in the accompanying drawings is adapted for use with an addressing machine as, for example, of the kind disclosed in the Duncan Patent No. 1,301,237, patented April 22, 1919 which is a hand-operated machine, but it is to be understood that the invention is equally adaptable for use with power-operated machines. The mechanism includes a housing 5 having a two-part printing form therein comprising dies 6 and 7. The housing 5 is mount-

ed at the outer end of an arm 8 which extends from a housing 9 and below the anvil A at printing position in the machine. A printing device D rests on the anvil to have a printing operation performed therefrom through the ink ribbon R stretched thereover by the usual platen P of the printing machine. The arm 8 and the housing 5 are so disposed that the dies 6 and 7 are arranged at one side of the anvil. The die 6 is fixedly mounted in the housing 5 while the die 7 is movable relative thereto and normally a portion of the die 7 extends above the plane of the die 6 and the face of the die 6 lies in the plane of the printing device D whereby at the time the platen P is making an impression from the printing device D the platen P', associated with the platen P, will be making an impression from the dies 6 and 7. The platen section P' may be detachable from the platen P so that it may be removed when it is not desired to make impressions from the dies 6 and 7. The die 7 is in the form of an elongated strip and has an opening 9 therein adjacent the lower end thereof into which the lever 10, fast on the shaft 11, is extended. The shaft 11 extends from the housing 5 through the arm 8 into the housing 9 and the medial portion of the shaft 11, disposed in the arm 8, is reduced to minimize friction. A spring 12 is disposed about the shaft 11 and one end thereof is connected to a lever 13, fast on the shaft, and the other end of the spring is secured to a fixed pin 14 in the housing 9. The die 7 lies in the path of movement of the platen P' and when the platens move into position to perform a printing operation the die 7 will be moved downwardly thereby until the face thereof lies in the plane of the die 6 and the printing device D. This downward movement of the die 7 is transmitted through the lever 10 to the shaft 11 and rotation of this shaft moves the lever 13 from position on the horizontal center line shown in Fig. 2 to position on the inclined center line and this downward movement may be utilized to operate a suitable device associated with the machine. For example, it may be employed to operate a sheet feed or a sheet ejector but in the present instance this movement is utilized

to operate a counting device of the common type. The lever 13 and the die 7 are retained in normal position when the platen P ascends by the spring 12 for this spring is wound when the lever 13 moves as before described and is therefore placed under tension. Consequently when pressure is relieved from the die 7, this spring will tend to unwind and reposition the parts and it will hold the parts in normal position, that is to say, with the die 7 extending beyond the plane of the die 6. The counting device is generally indicated by 15 and is mounted in a housing 15' fast on one of the frame members 16 of the printing machine. The operating arm 17 of the counting device is connected to the lever 13 by a link 18 which extends through a hollow arm 19 that has opposite ends thereof connected to the housings 9 and 15'. Preferably the housing 15' is closed so that unauthorized access thereto is prevented, a window 20 being provided in said housing through which the counting device may be read. When the lever 13 moves in the manner previously described, the link 18 is moved downwardly and consequently the operating arm 17 is moved from engagement with the positioning stop and from the center line position shown in Fig. 2 into the other center line position which causes operation of the counting device. As soon as the platen P' starts to ascend, the spring 12 will tend to unwind, whereupon the lever 13 and consequently the link 18 and arm 17 will be restored to their normal positions.

33 The auxiliary printing mechanism can be conveniently used for franking purposes and may be employed either as a stamp cancelling device or it may be used to print the postal marking. It is for this reason that the counting device is enclosed so that unauthorized access thereto may be prevented and therefore by taking readings from time to time postal authorities may ascertain what changes are to be made or the counting device may be operated for other purposes. The franking form is partly provided on the die 6 and partly on the die 7 and consequently when the form of the die 7 is depressed into the plane of the die 6 the complete form will be printed and whenever the die 7 is depressed the counting device will be operated. However, if for any reason the die 7 does not extend above the die 6 so that the depression thereof will operate the counting device, the mechanism is so arranged that only the portion of the form provided on the die 6 will be printed for the die 7 is arranged to fall below the plane of the die 6. It is apparent that the die 7 is directly connected to the counting device through the lever 10, shaft 11, lever 13, and link 18, and it is also apparent that it is the spring 12 which holds the die 7 in a plane above the die 6. Therefore, should this spring break the die 7 will fall and as stated it is so arranged that it

will fall below the plane of the die 6 and consequently the entire form will not be printed upon operation of the platen P'. Therefore, the postal authorities or others interested may readily ascertain whether or not the counting device is being operated, for if the die 7 is not operated in the manner desired only the portion of the form appearing on the die 6 will be printed and since this is incomplete detection is easy.

In the foregoing description we have set forth a selected embodiment of our invention but it is to be understood that this is capable of variation and modification and we therefore do not wish to be limited to the precise details set forth but desire to avail ourselves of such changes and alterations as fall within the ambit of the following claims.

We claim:

1. A printing mechanism including a printing die embodying fixed and movable parts having a printing form distributed thereon, and means including a yieldable device and holding the movable part in cooperative relation with the fixed part, said movable part being free to move relative to said fixed part upon failure of the holding means to position the portion of the printing form on the movable part out of cooperative relation with the portion of the form on the fixed part.

2. In a printing mechanism including a printing die embodying fixed and movable parts having a printing form distributed thereon, means including a yieldable device and holding the movable part in an extended position relative to the fixed part whereby the movable part is moved to position the portion of the printing form thereon in cooperative relation with the portion of the printing form on the fixed part upon application of printing pressure, said movable part being free to move relative to said fixed part upon failure of the holding means to position the portion of the printing form on said movable part out of cooperative relation with the portion of the form on the fixed part, and operative means independent of the printing form and connected with the movable part to be operated upon movement of said movable part against the action of the holding means.

3. In a printing mechanism including a printing die embodying fixed and movable parts having a printing form distributed thereon, a housing enclosing the lower portion of said parts and having an extension extending therefrom, a second housing at the end of said extension, holding means arranged in said housings and said extension and including a yieldable device, said means holding the movable part in an extended position relative to the fixed part whereby the movable part is moved against the action of said holding means to position the portion of

the printing form thereon in cooperative relation with the portion of the printing form on the fixed part upon application of printing pressure, operative means in the second housing, and means in the second housing connecting the operative means to the holding means so that the operative means is operated upon movement of said movable part against the action of said holding means.

4. In a printing mechanism including a printing die embodying fixed and movable parts having a printing form distributed thereon, means including a yieldable device and holding the movable part in an extended position relative to the fixed part whereby the movable part is moved to position the portion of the printing form thereon in cooperative relation with the portion of the printing form on the fixed part upon application of printing pressure, a counting device, and means connecting the movable part to the counting device so that said counting device is caused to accumulate upon movement of said movable part against the action of the holding means, said movable part being free to move relative to said fixed part upon failure of the holding means to position the portion of the form on said movable part out of cooperative relation with the portion of the form on the fixed part whereby an impression is not made from the complete printing form and said counting device is not caused to accumulate when said movable part moves out of cooperative relation with the fixed part upon failure of the holding means.

5. In a printing mechanism including a printing die comprising fixed and movable parts having a printing form distributed thereon, an operative device independent of said printing form and including an operating lever, another lever connected to said movable part, means interconnecting said levers, and yieldable means cooperating with said connecting means and holding said levers in a predetermined position, said movable part being free to move relative to the fixed part to position the portion of the form thereon out of cooperative relation with the portion of the form on the fixed part, and said yieldable means acting through the other lever to hold said movable part in cooperative relation with the fixed part whereby upon failure of said yieldable means said movable part may move to position the portion of the form thereon out of cooperative relation with the portion of the form on the fixed part.

6. In a printing mechanism including a printing die embodying fixed and movable parts having a printing form distributed thereon, a housing enclosing the lower portions of said parts and having an enclosed extension extending therefrom, a second housing at the end of said extension, holding means arranged in said housings and said extension and including a yieldable device

and means supporting a portion of the holding means for rotative movement, said holding means holding the movable part in extended position relative to the first part whereby the movable part is moved against the action of the holding means to position the portion of the printing form thereon in cooperative relation with the printing form on the fixed part upon application of printing pressure, a counting device, a housing enclosing said counting device and having an extension extending to the second housing, a lever connected to the rotative part of said holding means, a link extending through the extension of the housing enclosing the counting device and connected to said counting device, said lever and link acting to operate said counting device upon movement of the movable part against the action of the holding means, said yieldable device repositioning said movable part and said link and lever upon relief of printing pressure.

7. In a printing machine which has an anvil supporting a printing device in printing position and a platen for making impressions from said printing device, the combination therewith of a printing mechanism including a printing die embodying fixed and movable parts having a printing form distributed thereon, the portion of the printing form on the fixed part being disposed substantially in the same plane as the printing device on the anvil, means including a yieldable device and holding the movable part in extended position relative to the fixed part whereby the movable part is moved to position the portion of the printing form thereon in the same plane as the portion of the printing form on the fixed part upon application of printing pressure by said platen in an operation thereof to make an impression from said printing device and printing form, said movable part being free to move relative to said fixed part upon failure of the holding means to position the portion of the printing form on said movable part out of the plane of the portion of the form on the fixed part so that an impression is not made from the portion of the form on the movable part upon operation of said platen.

8. In a printing machine which has an anvil supporting a printing device in printing position, a platen for making impressions from said printing device, and a counting device, the combination therewith of a printing mechanism including a printing die embodying fixed and movable parts having a printing form distributed thereon adapted for cooperation with the platen, the portion of the printing form on the fixed part being disposed in substantially the same plane as the printing device on the anvil, means including a yieldable device and holding the movable part in extended position relative to the fixed part whereby the movable part is

moved to position the portion of the printing form thereon in the same plane as the portion of the printing form on the fixed part upon application of printing pressure by said platen in an operation thereof to make an impression from said printing device and said printing form, connecting means interconnecting said movable part and the counting device whereby the counting device is caused to accumulate each time the platen makes an impression from the printing form on said fixed and movable parts, said movable part being free to move relative to the fixed part upon failure of the holding means to position the portion of the printing form on said movable part out of the plane of the portion of the form on the fixed part so that an impression is not made from the portion of the form on the movable part upon operation of said platen and said counting device is not caused to accumulate.

9. In a printing machine which has an anvil supporting a printing device in printing position, a platen for making impressions from said printing device, and a counting device, the combination therewith of a housing having a printing die extending therefrom, said printing die embodying fixed and movable parts having a printing form distributed thereon adapted for cooperation with the platen and having the portion of the printing form on the fixed part disposed substantially in the same plane as the printing device on the anvil, said housing including an arm extending past said anvil to a second housing, holding means arranged in said housings and said arm and including a shaft supported for rotative movement, means connecting said shaft to said movable part, and a spring acting on said shaft to hold the movable part in an extended position relative to the fixed part whereby the movable part is moved to position the portion of the printing form thereon in the same plane as the portion of the printing form on the fixed part upon application of printing pressure by said platen in an operation thereof to make an impression from said printing device and printing form, a housing enclosing said counting device, a hollow arm connecting the second housing and the housing enclosing the counting device, a lever in the second housing connected to said shaft, a link extending through said hollow arm and interconnecting said lever and said counting device, the movement of said movable part upon operation of said platen being transmitted through said rotatable shaft, lever, and link to said counting device to operate said counting device upon each operation of said platen.
